UNITED STATES PATENT OFFICE.

WILLIAM H. McDAVITT, OF LAWRENCE, ASSIGNOR TO GEORGE DRAPER & SONS, OF HOPEDALE, MASSACHUSETTS.

BANDING-MACHINE.

SPECIFICATION forming part of Letters Patent No. 473,886, dated April 26, 1892.

Application filed October 5, 1891. Serial No. 407,764. (No model.)

To all whom it may concern:

Be it known that I, WILLIAM H. McDAVITT, of Lawrence, county of Essex, State of Massachusetts, have invented an Improvement in 5 Banding-Machines, of which the following description, in connection with the accompanying drawings, is a specification, like letters and figures on the drawings representing like parts.

10 This invention has for its object to simplify and improve the construction of that class of machine employed in twisting bands to be employed for driving spindles and the like.

15 My invention is applicable to twisting two or more strands into cords for various uses.

20 My invention consists, essentially, in the combination, with a traveling carriage having a hook for the reception of the central part of the strands to be twisted together in the formation of a band, of an automatically-operated latch consisting of a tilting lever placed in the path of movement of and to arrest the backward movement of the carriage and means constantly acting to place said lever in 25 the path of the carriage, as and for the purpose set forth.

Figure 1 in side elevation represents a sufficient portion of a banding-machine to enable my invention to be understood. Fig. 2 is a 30 top or plan view of the machine shown in Fig. 1, and Fig. 3 is an enlarged perspective detail showing a latch embodying my invention.

The bed A of the machine, the shaft B, having the loose and fast pulleys C D, the revolving head W, containing the pinions d d, the twisting-hooks G, upon which the said pinions d are attached, the carriage J, the guide-rods U, on which it slides, the cord a, attached to the said carriage, the pulley b, over which 40 the cord is extended, and the weight Q are and may be all substantially as common and as described by like letters in Patent No. 391,728, granted October 23, 1888. The carriage J has extended from it, as herein shown, 45 a hook c to receive the folded or closed end of the band, the cord or equivalent a being engaged with a suitable hook a', also connected to said carriage.

In accordance with my invention I desire 50 to provide means whereby, when the operator releases the looped end of the band from the

hook c, the carriage will not immediately run back to the end of the bed, but will remain in easy reach of the operator until after a new cord to be twisted has been applied, when the carriage will be permitted to move backward to put the proper strain upon the cord preparatory to twisting it. 55

In the form in which I have herein represented my invention I have erected upon the bed A a suitable stand e, and upon this stand I have mounted a latch e', it having, as represented, a beveled or inclined portion e², the latch preferably having a weight, as e³, to normally keep its inner or beveled end up within 60 range of a pin or projection e⁴, which I have added to the usual carriage J, the said carriage in practice having a handle 2. 65

In operation let it be supposed that a cord for the production of a band has been applied 70 to the twisting-hooks and to the hook c and that the carriage before twisting the band occupies a position with the projection e⁴ more or less back of or to the right of the latch e' in Fig. 1. Now as the cord is twisted in the 75 formation of the band the carriage is drawn to the left, viewing Fig. 1, or in the direction of the arrow thereon, and the projection e⁴ of the carriage during its movement in the direction referred to will strike the inclined 80 side of the latch and will tip or depress the same, so that the projection e⁴ will pass the latch, as herein represented, and the weight e² will immediately and automatically cause the latch to fly up at this time behind the projection e⁴. The carriage will continue to travel 85 in the direction stated until the band has been sufficiently twisted, when the operator will detach the looped end 3 of the band from the hook c preparatory to detaching the opposite 90 end of the band from the twisting-spindle. In accordance with my invention, however, when the looped end of the band, or it may be the other end, is disconnected, as stated, from the devices holding it when being twisted 95 the carriage, acted upon by the weight Q, will move back, or to the right in Fig. 1, only until the projection e⁴ meets the latch. Arresting the backward movement of the carriage at an intermediate point, as stated, leaves the hook 100 c in easy reach of the operator when about to apply a new cord to the twisting-hooks and

to the hook *c*, so that the operator does not have to walk two or three steps to the right, as is sometimes the case, to engage the carriage and bring it forward to the left and hold it there by hand while the band is being connected with the hook *c*. The new cord having been applied, the operator will engage the latch, turn it, and let the weight *Q* move the carriage to properly stretch the cord before the commencement of the twisting operation.

Prior to this invention I am not aware that the backward movement of the carriage has been arrested temporarily, as described, to hold it in an intermediate position while the twisted band is being removed and a new cord applied to the twisting devices, so it is not intended to limit this invention to the exact construction of the parts shown; but instead I may use any equivalent—as, for instance, a spring—for the weight, and the shape of the latch and its incline may be more or less varied and yet be within the scope of this invention.

For the sake of lightness I have provided

the carriage *J* with the projection *e*⁴. This projection forms part of the carriage and may be of any suitable shape so as to present an engaging portion to act upon and be acted upon by the carriage.

Having described my invention, what I claim, and desire to secure by Letters Patent, is—

In a banding-machine, a traveling carriage having a hook for the reception of the central part of the strands to be twisted into a band, combined with an automatically-operating latch consisting of a tilting lever placed in the path of and adapted to arrest the backward movement of the carriage and means constantly acting to place said lever in the path of the carriage, as and for the purpose set forth.

In testimony whereof I have signed my name to this specification in the presence of two subscribing witnesses.

WILLIAM H. McDAVITT.
